ATTORNEY.

UNITED STATES PATENT OFFICE.

ALBERT E. PALMER, OF OWOSSO, MICHIGAN, ASSIGNOR TO LYMAN E. WOODARD, OF SAME PLACE.

COFFIN-FASTENER.

SPECIFICATION forming part of Letters Patent No. 424,346, dated March 25, 1890.

Application filed December 26, 1889. Serial No. 335,006. (No model.)

To all whom it may concern:

Be it known that I, ALBERT E. PALMER, a citizen of the United States, residing at Owosso, in the county of Shiawassee and State of Michigan, have invented certain new and useful Improvements in Casket or Box Fasteners; and I do hereby declare that the following is a full, clear, and exact description of the same, reference being had to the annexed drawings, 10 making a part of this specification, and to the letters of reference marked thereon.

This invention relates to certain new and useful improvements in fastenings for caskets or boxes or other like receptacles; and it has 15 for its object, among others, to provide a simple and cheap fastener which shall be efficient in operation, being automatic in closing, and being so constructed as to absolutely prevent accidental unlocking, as by jars or jolts, during 20 transportation of the casket or box to which it is applied.

Former fasteners have been found objectionable for several reasons. They cut too deep into the wood and have too little action, and 25 are not sure to catch or latch and are too easily unlatched.

My fastener avoids all the above objections.

The novelty in the present instance resides 30 in the peculiarities of construction and the combinations, arrangement, and adaptation of parts, all as more fully hereinafter described, shown in the drawings, and then specifically pointed out in the appended claims.

The invention is clearly illustrated in the 35 accompanying drawings, which, with the letters of reference marked thereon, form a part of this specification, and in which—

Figure 1 is an enlarged sectional view 40 through two parts locked by means of my improved fastener on the line $x-x$ of Fig. 2. Fig. 2 is a section taken at right angles to that of Fig. 1. Fig. 3 is a perspective view of the upper side of the locking-plate and its attached parts, parts being broken away to better show other parts.

Like letters of reference indicate like parts throughout the several views.

Referring now to the details of the drawings by letter, A designates a keeper attached to 50 one of the parts—as, for instance, the upper edge of the body of a casket B. Beneath this keeper there is a recess to receive the locking-

jaws hereinafter described. The plate or keeper is secured in a suitably-countersunk seat on the upper edge of the casket-body by 55 means of suitable screws, nails, or other fastenings, as a.

C is a plate adapted to be secured in a suitably-countersunk seat in the other part, which, for instance, we will suppose to be the lid of 60 the casket, by means of suitable screws, nails, or other fastenings. This plate is formed with a slot b, through which pass the depending lugs c, which have latch ends d, as shown best in Fig. 1. The latches on the two arms 65 D extend in opposite directions, as shown in Fig. 1. At one end these arms extend beyond the plate and are formed with thumb-pieces e at said ends, the other ends of the said arms being formed with hooks f to engage the portions f' of the plate F.

F is a plate covering the major portion of these arms and secured to the plate C by means of a screw, so as to be readily detached when desired. This plate is tapered, being 75 wider at one end than at the other, and at the narrow end engaged by the hooks on the inner ends of the arms D to prevent displacement thereof.

G is a stud on the plate C, projecting 80 through the plate F, and against which the arms D contact at their recessed portions g when the said arms are brought together to unlock the parts.

H is a spring, substantially U-shaped, arranged within the covering-plate F, with its bend around the screw that secures the said plate to the plate C, and with its ends acting upon the two arms D, as shown best in Fig. 3.

Projecting from the under side of the plate 90 C is a looped portion J, within which the catches of the arms D work, as shown in Fig. 2.

The operation is simple and apparent. The spring acting on the arms D serves to at all times keep the thumb ends thereof separated 95 or spread out, as shown in Fig. 3, thus keeping the latch or latches thereof under and in contact with the keeper-plate, as shown in Fig. 1. When it is desired to unlock the parts, the arms D are brought together by the hand against the tension of the spring, and this brings the latches of the arms within the loop J, when the parts may be readily separated.

In some cases I prefer to make one lever stationary, omitting the latch thereon, and such other changes in the details of construction I reserve the right to make as would 5 come within ordinary mechanical skill and not affect the principle of my invention.

What I claim as new is—

1. The plate having upon its under side a looped portion, combined with arms connected to said plate and provided with a depending latch or latches passed through a slot in the plate and working through said looped portion, and a spring between said latches, as set forth.
- 15 2. The combination, with the plate C, formed with a depending loop, of the arms having at

one end thumb-pieces and at the other end formed with hooks, and formed between the said ends with depending latches working through a slot in the plate and within the 20 loop, a plate over the arms and engaging the said hooks, and a spring beneath the covering-plate, with its ends bearing on said arms, substantially as and for the purpose specified.

In testimony that I claim the above I have 25 hereunto subscribed my name in the presence of three witnesses.

ALBERT E. PALMER.
